UNITED STATES PATENT OFFICE.

CÆSAR A. CUPPIA, OF NEW YORK, N. Y.

DESIGN FOR A CONDIMENT-HOLDER.

SPECIFICATION forming part of Design No. 28,259, dated February 8, 1898.

Application filed November 20, 1897. Serial No. 659,337. Term of patent 3½ years.

To all whom it may concern:

Be it known that I, CÆSAR A. CUPPIA, a citizen of the United States, residing at New York city, in the county and State of New York, have invented and produced a new and original Design for a Condiment-Holder, of which the following is a specification, reference being had to the accompanying drawing, forming a part thereof, which represents a

5 side elevation of a receptacle embodying the features of my design.

The design consists of the body A, representing the crown of a stag-horn, the body being apparently connected with the top B and the base C, the top and base framing the body.

The design is applicable to all kinds of

handleless vessels—such as salt, pepper, and mustard boxes, muffineers, &c.

The leading feature of the design consists 20 of the stag-horn body A, apparently connected with a top and a base, the top and the base framing the body.

As a further feature of the design the top B and the base C are provided with outlines 25 that contrast with the outline of the body.

I claim—

The design for a condiment-holder, substantially as herein shown and described.

CÆSAR A. CUPPIA.
